UNITED STATES PATENT OFFICE.

ALEXANDER WALKER BEERS, OF BETHLEHEM, PENNSYLVANIA.

FOLDING PACKAGE OR POCKET-BOOK.

SPECIFICATION forming part of Letters Patent No. 657,687, dated September 11, 1900.

Application filed November 23, 1899. Serial No. 738,567. (No model.)

To all whom it may concern:

Be it known that I, ALEXANDER WALKER BEERS, a citizen of the United States, residing at Bethlehem, in the county of Northampton 5 and State of Pennsylvania, have invented certain new and useful Improvements in Folding Packages or Pocket-Books, of which the following is a full and complete specification, such as will enable those skilled in the art to 10 which it appertains to make and use the same.

This invention relates to folding packages or boxes of that class which are formed from a single sheet or blank which is adapted to be folded up into operative position.

15 The object of my invention is to provide a simple and improved device of this character which will be conveniently adapted for use or service as a pocket-book, which will not open out flat, so that there is risk of the loss 20 of the contents, which will be adapted to permanently retain its shape after being folded and locked, which can be very rapidly and conveniently folded into operative position, which will have the general appearance 25 in use of a pocket-book, but will be devoid of all sewing or gluing of any character, and which will also be more serviceable, efficient, and convenient than the ordinary devices of this class which are now in use.

30 In the accompanying drawings, forming a part of this specification, in which like numerals of reference denote corresponding parts in the several views, Figure 1 is a plan view of the blank from which the device is 35 formed. Fig. 2 is a rear elevation of the device when in folded position, the interior folds of the front lock being illustrated in dotted lines; and Fig. 3 is a transverse sectional view taken on the line $\alpha\alpha$ of Fig. 2.

40 Referring to the drawings, 1 designates the blank or sheet from which my improved folding pocket-book or package is formed, said blank or sheet being cut out in a single piece from paper or other suitable material. 45 The blank 1 comprises a rectangular main portion or body 2, adapted to form the front and back, bottom and top, and inner and outer locking-flaps of the body portion of the package, and from said portion 2 at opposite 50 sides extend side flaps or portions 3 3, which are adapted to form the sides and collapsible side portions and front lock of the package.

or pocket-book. The main or body portion 2 comprises a rectangular part 4, adapted to form the back of the device, and a corresponding rectangular part 5, adapted to form the front of the device, these parts 4 and 5 being connected by an intermediate rectangular part or portion 6, divided from the parts 4 and 5 by parallel transverse scoring or creasing, as at 7 7, and adapted to form the bottom of the device. 8 designates the front flap, having a projecting locking-tongue 9, said flap 8 being divided from the part 4 by a rectangular portion 10, formed by parallel 60 scoring or creasing, as at 11 11, and adapted to form the top of the device. The part 5 carries a projecting flap 12, having opposite side tongues 13 13 and adapted to form an inner front lock, as will be hereinafter 65 described, said flap 12 being connected with the part 5 by means of a transverse single line of scoring or creasing, as at 14. The side-wing portions 3 3 respectively comprise a central or intermediate rectangular portion 15, forming 70 an extension of the corresponding part 6 and formed by parallel scorings or creasings, as at 16 16, which are an extension of the scorings 7 7. Said portions 15 are adapted to 75 form the sides of the device and are connected 80 with the part 6 by means of scorings or crease-lines, as at 17 17, extending at right angles to the scorings 7 and 16. The portion of the side flaps 3 above the part 15 is adapted to 85 form the collapsible side portions of the device. This portion is connected by scorings or crease-lines, as at 18 18, with the part 4, and it is radially creased or scored between the lines 18 and 16, as indicated at 19, said 90 lines 19 converging from the point of junction between the lines 18 and 16, and the outer portion of said radially scored or creased part being cut off or beveled, as indicated at 20. The portions of the side flaps 3 below the parts 15 are separated from the part 5 for the full 95 extent of their inner edge by a cut or kerf, as indicated at 21, and said separated portions are respectively provided in the outer edge and the inner edge with a slit or recess, as at 22, which is preferably approximately 100 V-shaped and which forms an interlocking portion, as will be hereinafter described. In said separated portions are respectively formed diagonally-arranged slots, as at 23,

adapted to respectively receive the tongues 13 of the flap 12, and in the part 5 is provided a segmental slot or slit 24, adapted to receive the tongue 13 of the flap 8.

5 The operation and advantages of my invention will be readily understood by those familiar with the art to which it appertains. The blank 1 may be conveniently and inexpensively cut from a single sheet or piece of 10 paper or other adapted material, and the various scorings or crease-lines, as hereinabove described, may be conveniently formed in any desired or adapted manner. To fold the package or pocket-book from the blank into 15 operative position, it is only necessary to first bring the side-flap portions 3 3 into position at right angles to the parts 4 and 5, which is done by merely folding the crease-lines 18 and 17, and in which position the side or end portions 15 15 will project up at right angles to the bottom portion 6. The lower separated 20 portions of the side flaps 3 3 may now be brought inwardly, so that they project upwardly at right angles to the bottom portion 6, with their lower edges registering with the 25 lower crease-line 7, and the respective recesses 22 may be engaged to lock said lower flap portions in connected position. The adjustment of the lower portions of the flaps 3 3 30 into position, as just described, is effected by merely bending the lower crease-lines 16. The front portion 5 of the body 2 is now brought up in front of the connected flap portions last described by bending at the 35 lower crease-line 7, and the flap 12 is turned over the top edge of said just-described connected flap portions by bending at the crease-line 14 and turned downwardly within the body of the device and in rear of said connected flap portions, when its side tongues 13 40 may be engaged with slots 23 to lock the front portion of the device and retain the same securely in folded position and at the same time protect the top edge at the front. 45 The device may now be folded into closed normal shape by simply bending at the upper crease-line 7 and the upper crease-lines 16, in which folding operation the diagonally-creased portions 19 will fold inwardly. When 50 in the position as now described, the body of the device will maintain a square or rectangular contour, it being firmly locked in this position. At the same time it can also be sep-

arated into open position by action of the folds 19; but it cannot be opened out flat, 55 (which operation is precluded by the interlocked condition of the front portion, as will be readily understood,) thus entailing risk of the loss or disarrangement of the contents. To close the device, it is only necessary to 60 bend the top portion 10 over at the lower crease-line 11 and then to turn the flap 8 downwardly at the front by bending the upper crease-line 11, when the tongue 9 may be engaged within the slot 24. 65

It will be observed that the device as comprised in my invention and improvements will have the general appearance of a sewed pocket-book; but at the same time it will be formed by merely folding a single sheet or blank without sewing or gluing of any character and that it is securely locked in operative position and at the same time prevented from opening out flat when in use.

Having fully described my invention, I 75 claim as new and desire to secure by Letters Patent—

The herein-described package or pocket-book of the class mentioned, formed of a single sheet or blank provided with scoring or crease-lines for folding, and comprising the back 4, the bottom 6, the front 5, the top 10, the front flap 8, and the inner flap 12, said foregoing portions constituting serially the main or body portion, the side-flap portions 85 projecting at opposite sides of said main or body portion and consisting respectively of the upper portion extending laterally from the back 4, the end 15, and the lower portion connected with the end 15 and extending from 90 said end in a position at the side of the front 5, said lower portions of the side flaps and the front 5 being disconnected at their adjoining edges, the front flap 8 being adapted to engage with the front 5 and the inner flap 12 95 being adapted to engage said lower portions of the side flaps, substantially as and for the purpose set forth.

In testimony that I claim the foregoing as my invention I have signed my name, in presence of the subscribing witnesses, this 20th day of November, 1899.

ALEXANDER WALKER BEERS.
